(57) CLAIM

The ornamental design for an eating utensil, as shown and described herein.

DESCRIPTION

FIG. 1 is a perspective view of the eating utensil of the instant invention, showing the new design;

FIG. 2 is a bottom plan view of the instant invention of FIG. 1;

FIG. 3 is a top plan view of the instant invention of FIG. 1;

FIG. 4 is a front elevational view of the instant invention of FIG. 1, the rear elevational view being a mirror image thereof; and,

FIG. 5 is a right side elevational view of the instant invention of FIG. 1, the left side being a mirror image thereof.

1 Claim, 1 Drawing Sheet
